UNITED STATES PATENT OFFICE.

EMIL HUBER, OF DETROIT, MICHIGAN, ASSIGNOR TO ESSEX MOTORS, OF DETROIT, MICHIGAN, A CORPORATION OF MICHIGAN.

CARBURETER.

1,344,696.

Specification of Letters Patent. Patented June 29, 1920.

Application filed May 15, 1916. Serial No. 97,552.

To all whom it may concern:

Be it known that I, EMIL HUBER, a citizen of the United States, residing at Detroit, county of Wayne, State of Michigan, have 5 invented a certain new and useful Improvement in Carbureters, of which the following is a specification, reference being had therein to the accompanying drawings.

My invention has for its object an improvement in carbureters by which liquid fuel and air are mixed preparatory to consumption in an internal combustion engine. More particularly, the invention relates to 10 means for automatically regulating the supply of fuel and the amount of air and the proportions thereof, by means of the suction in the inlet manifold, thereby causing them to conform more exactly to the varying requirements of the engine. Also, the invention has to do with means for increasing 15 or diminishing the amount of fuel in proportion to the amount of air, said change when once made being effective for all speeds. The mechanism by which this is 20 accomplished may be operated from the driver's seat and therefore forms a convenient dash board adjustment to compensate for changes in atmospheric conditions 25 when the carbureter is used for motor vehicles.

The carbureter which is shown and described in this application is an improvement on the carbureter shown in my prior Patent No. 708,949 dated Jan. 24, 1905. In 30 that patent there is shown a fuel supply control device which consists of a rod sliding in a stuffing box and having a cylindrical bore throughout a portion of its length said bore terminating in a groove of diminishing cross-section. This rod was moved 35 by the operator to control the supply of fuel. This patent also shows an air valve comprising a cylindrical member (not a piston) having on opposite sides thereof 40 triangular openings cooperating with openings in the carbureter casing to control the flow of air through the carbureter. This air valve was moved by the operator and performed the two functions of a throttle 45 valve and of controlling the amount of air in the mixture. The effect of this mechanism is that the air valve throttle and fuel

valve are set to the correct position for a given speed before the engine attains that speed and therefore there is a moment during which the carbureter is imperfectly adjusted to the engine speed. 55

In the carbureter shown in the drawings accompanying this application, I provide an air valve and a fuel valve which are 60 moved by a piston which is moved in response to variations in the suction in the inlet manifold. The fuel supply valve comprises a rod sliding in a cylindrical orifice and has a groove of constantly diminishing 65 cross-section extending lengthwise thereof. This fuel measuring rod is connected to the air valve and moved in unison therewith so that as the air passage is enlarged or diminished, the supply of fuel is correspondingly 70 and automatically varied. Since the air valve and fuel supply valve are moved by the piston which is actuated by the change in pressure in the inlet manifold, the change in position of these parts follows instead of 75 precedes the change in speed of the engine depending for its position on the suction in the inlet manifold. This gives the engine much increased power of acceleration. The orifice in which the fuel measuring rod 80 slides is formed in a tube which is itself movable longitudinally of the rod for purposes of adjustment, preferably by connections to the dash board of the vehicle. By moving this tube, a change in the amount 85 of fuel relatively to the amount of air is produced, and this relation is thereafter maintained for all speeds of the engine.

I find from observation of the action of my improved carbureter in actual use that 90 a perfect mixture of correct proportions of fuel and air is maintained at all speeds and that any necessary adjustment may be quickly and accurately made by moving the tube relatively to the rod by means of the 95 adjusting mechanism within the reach of the operator are effected. The novel construction herein described gives much more perfect and more uniform atomization than other carbureters known to me and, therefore, great fuel economy and uniform engine operation. Since the carbureter has 100 only one means of adjustment, it is not likely to get out of order even when in the

2
hands of inexperienced users. It is also relatively inexpensive to manufacture. The great accuracy with which the fuel and air may be proportioned to each other results in great fuel economy.

5 Figure 1 is a view in elevation of a carbureter embodying my invention.

Fig. 2 is a vertical section of the carbureter shown in Fig. 1. The construction of 10 the float valve and chamber is not shown in detail as the same forms no part of my present invention.

Fig. 3 is a vertical section taken at right angles to the section forming Fig. 2.

15 Fig. 4 is a section on line 4—4 of Fig. 2.

Fig. 5 is a section of the combined piston and air valve and the connected fuel supply control rod.

20 Fig. 6 is a section on line 6—6 of Fig. 5.

Fig. 7 is a section of the inner casing showing the shape of the air passage.

25 Fig. 8 is a detail of the movable tube which co-operates with the fuel supply control rod.

In the drawings, there is shown at 11, the float chamber and at 12 the connection to the fuel supply line. The casing of the carbureter is formed in two parts 13 and 14 the former being called for convenience 30 the outer casing and the latter (see Fig. 7) the inner casing. The lower end of the inner casing 14 passes through an annular collar 15 formed integral with an arm 16 on which the float chamber is supported and 35 through which a passage leads from the float chamber to a space 17 formed between the annular collar 15 and the lower end of the inner casing 14. The parts are secured together by a cap 18 having a threaded portion 40 which engages a correspondingly threaded part of the lower end of the inner casing 14. A port 19 leads from the annular space 17 to the bore 20 of the cap. At 21 is shown a pet cock by which the carbureter may be drained.

45 Within the bore of the inner casing 14 is located a tube or nozzle 22 (see also Fig. 8) which is movable vertically to vary the position of its upper end. The tube 22 is formed with a series of rack teeth 23 which mesh with a small pinion 24 mounted on a shaft 25 which projects through the stem of the inner casing of the carbureter. This shaft 25 is provided with an arm 26 by 50 which it may be moved and which is adapted for connection with suitable operating means (not shown) located preferably within the reach of the operator of the vehicle. This construction makes possible convenient and accurate adjustment of the tube 55 22 vertically for purposes which will be fully explained.

60 The outer casing 13 is provided with a flange 27 by which the carbureter is secured to the engine, and has an air intake 28 lo-

cated on the opposite side of the carbureter from the flange 27. The inner casing 14 projects up into the interior of the outer casing being centered by a shoulder 29 on the inner casing, and having an annular 70 space between the two casings as shown at 30 in Fig. 2. The air passage through the carbureter from the intake to the flanged end is in the shape of a triangular prism, the apex of the triangle being down. This 75 passage in the inner casing is formed by two diverging sides 31 and 32 and a top 33. The shape of the end of the air passage is clearly shown in Fig. 7. The portions of the outer casing which are adjacent the ends 80 of the air passage in the inner casing are also of similar shape.

It will be seen that the passage through the carbureter is perfectly straight and therefore the air passing through the carbureter has a high velocity which is important at high speeds, and greatly improves the atomization.

At 340, is shown the usual butterfly valve or throttle valve by means of which the air 90 passage may be closed at a point in the air passage where it is circular in cross section. For convenience, the portion of the casing in which is located the throttle valve is referred to herein as the inlet manifold. 95

The tube or nozzle 22 is disposed centrally of the triangular air passage through the casing and may be raised so that its upper end will be above the bottom of the air passage an amount controlled by the 100 operator of the vehicle.

The upper part of the outer casing 13 is formed into a cylinder 34 closed by a cap 35. An air duct 36 leads from the top of the cylinder 34 into the air passage or inlet manifold at a point between the spray nozzle 22 and the throttle valve. The air duct 36 is extended by a pipe 48 down into the air passage to a point near the bottom as shown in Fig. 3 so that at all positions 110 of the piston it will be subjected to the rush of air through the carbureter. Operating in the cylinder 34 is a combined piston and air valve 38 which is bell-shaped or in the form of an inverted cup having a depending flange portion the lower edge 39 of which serves as a cut-off for the air passing through the horizontal triangular air passage in the casing or port 14. Said air valve 38 is therefore practically a cylindrical one and the depending flange portion thereof has a sliding fit in the space formed between the inner casing 14 and the outer casing 13. These parts are constructed of such size that the piston 38 will fall and 115 rise by the alternate action of gravity and of the suction in the cylinder 34, resulting from its connection by the duct 36 with the inlet manifold. The portion of the air passage which lies between the two walls of 120 125 130

the combined piston and air valve 38 is within the casing and is determined by the shape which is given to this part of the casing and is preferably triangular in cross section as previously explained. This construction is such that the movement of the air through the carburetor will be at the greatest velocity possible and will not be diminished by air eddies.

10 The piston 38 has secured to it the fuel measuring rod 40 which has a lengthwise groove 41 formed in its lower end. This groove 41 is V-shape in cross section and of a diminishing cross section vertically as will be clearly seen from Figs. 3 and 5 and faces toward the engine. The lower end of the fuel measuring rod 40 is of a size to slide freely in the bore of the tube or nozzle 22. It therefore, forms with the tube 22, a fuel valve the opening of which is varied by the change in position of the rod 40, or of tube 22 or of both. As it is desirable that the groove 41 in the fuel supply rod 40 shall always face toward the inlet manifold, I provide two slots 43 in opposite sides of the piston, and these coöperate with two ribs 44 on the outside of the inner casing or part 14. These ribs keep the piston from rotating and also block the passage between the inner and outer casings which is formed when the piston is up, and which if not closed would allow a quantity of air to be introduced into the mixture at a point between the fuel supply valve and the throttle.

35 At 45 is shown a packing which is compressed against a loose ring 46 by means of a ring 47 screwed into the bore of the lower end of the inner casing. This serves to prevent any leakage of fuel upward around the outside of the nozzle 22, which would change the proportions of the mixture.

The operation of my improved carburetor is as follows: The liquid fuel, usually gasoline, enters through the pipe 12 and fills the 45 float chamber and rises in the nozzle 22 to about the position indicated by the line *a*, *a* in Fig. 1, this level being determined by the adjustment of the float in the ordinary manner. Before the engine is started, the piston 38 will be in its lowest position with its lower edge resting on the shoulder 42 (see Fig. 7) of the inner casing and therefore the triangular air passage will be closed except for the very small portion lying below the 50 shoulder 42 which can never be closed by the piston. When the engine is started and speeds up the increase in the vacuum in the inlet manifold will produce a corresponding increase in vacuum in the cylinder 34 with which it communicates by the duct 36 and the air pressure on the under side of the piston 38 will cause it to lift until it reaches a position of equilibrium.

65 It will be noticed that the mouth of the passage 36 enters the inlet manifold at a

point between the fuel nozzle and the throttle valve and not between the throttle valve and the engine, since if it entered at the latter point the high vacuum which is created when the engine is suddenly throttled down 70 would increase the vacuum above the piston and interfere with the proper operation of the engine. By carrying the passage down to the point shown, the piston is always subjected to a degree of vacuum which is proportional to the draft through the carburetor.

The movement of the piston vertically will open the triangular air passage and will simultaneously lift up the rod 40 increasing 80 the size of the orifice formed by the groove 41. The fuel supply will therefore be increased as the air supply increases and both will be dependent upon the suction through the carburetor and therefore on the speed of 85 the engine. By giving the groove 41 in the fuel measuring rod 40 the proper increase in cross section in proportion to its length having in mind the increase in cross section in the triangular air passage, a mixture of gaso- 90 lene and air which is correct at all positions of the measuring rod may be obtained.

It will be seen that when the throttle is opened, the position of the air valve and fuel measuring rod will not be changed until 95 after the engine has speeded up and reduced the pressure in inlet manifold, lifting the piston by which the air valve and fuel supply valve are actuated. Thereafter the position of the air valve and fuel measuring rod 100 will change as the draft through the carburetor varies.

By moving the lever 26 and lowering the tube 22, a mixture which is richer at all speeds will be produced because when this is 105 done there will be a larger fuel supply opening for every position of the air valve. By raising the tube 22, a mixture which is weaker at all speeds will be produced.

The carburetor embodying my invention 110 as herein described has proved very satisfactory in actual operation, giving increased power and better acceleration.

While I have shown the piston and air valve as formed integral, and the fuel supply 115 valve rigidly connected to the piston, I do not limit myself to this construction.

What I claim is:

1. In a carburetor, the combination of a casing having an open-ended horizontally 120 extending air passage therethrough, one end of said air passage communicating with the outer air and the other with an inlet manifold, a cross section of a portion of said air passage being of increasing width from the 125 bottom up and there being a fuel orifice at all times at or near the point of least width, and an air valve having a substantially straight lower edge intercepting said passage and movable transversely thereacross 130

to open and close the same, the direction of movement of said valve to open said passage being from the point of least width of cross section toward the point of greatest 5 width of cross section.

2. In a carbureter, the combination of a casing having an open-ended, straight, horizontally extending air passage therethrough one end of said air passage communicating 10 with the outer air and the other with an inlet manifold, a cross section of a portion of said air passage being of increasing width from the bottom up and there being a fuel orifice at all times at or near the point of 15 least width, and an air valve having a substantially straight lower edge intercepting said air passage and movable transversely thereacross to open and close the same, the direction of movement of said valve to open 20 said passage being from the point of least width of cross section toward the point of greatest width of cross section.

3. A carbureter having a casing formed with an air passage through the same, and 25 an air valve movable transversely of said air passage and having two portions which intercept the air passage at a distance from each other, the said air passage being triangular in cross section between the said 30 two portions of the valve.

4. A carbureter having a casing formed with a straight air passage through the same, and an air valve movable transversely of said air passage and having two portions which 35 intercept the air passage at a distance from each other, the portion of the said air passage between the sides of said air valve being formed in the casing.

5. A carbureter having a casing formed 40 with an air passage through the same, and a cylindrical air valve the sides of which are movable in a cylindrical slot in said casing to intercept the said air passage at two points at a distance from each other, the 45 portion of the said air passage between the sides of the cylindrical air valve being formed in the casing.

6. A carbureter having a casing formed with an air passage through the same, and 50 a cylindrical air valve the sides of which are movable in a cylindrical slot in said casing to intercept the said air passage at two points at a distance from each other, the said air passage being triangular in cross 55 section between the said two portions of the valve.

7. A carbureter having a casing formed with an air passage through the same and an air valve movable transversely of said 60 air passage and having two portions which intercept the air passage at a distance from each other, the said air passage being triangular in cross section between the said two intercepting portions of the valve and a fuel 65 valve having a fuel orifice located within

the said air passage between said flange portions.

8. A carbureter having a casing with an air passage through the same, a cylinder formed in the said casing and subjected to 70 changes in pressure in the intake manifold, and a piston air valve in the said cylinder slideable transversely of the said air passage and having two portions which intercept the air passage at a distance from each other, 75 said air passage being triangular in cross section between the said two portions of the valve.

9. A carbureter having a casing formed with an air passage through the same and an air valve slideable transversely of said air passage and having two portions which intercept the air passage at a distance from each other, the said air passage being triangular in cross section between the said two intercepting portions of the valve, and a fuel metering pin connected to the air valve and having its fuel orifice located between said 80 two portions of the valve, said metering pin being formed with a longitudinal groove 85 of increasing cross section therein.

10. A carbureter having a casing formed with an air passage through the same and an air valve slideable transversely of said air passage and having two portions which intercept the air passage at a distance from each other, the said air passage being triangular in cross section between the said two portions of the valve and having its apex away 95 from the valve and a fuel metering pin connected to and movable by said air valve and having formed therein a groove of increasing cross section forming a fuel orifice 100 located adjacent the apex of the air passage.

11. A carbureter having a casing with an air passage therethrough, a cylinder formed in the said casing and subjected to changes in pressure in the intake manifold, a piston air valve in the said cylinder the sides of which are movable in a cylindrical slot in 110 said casing to intercept the said air passage at two points at a distance from each other, the air passage between the sides of the cylindrical air valve being formed in the casing, and a fuel valve in the said air passage 115 between the sides of the air valve.

12. A carbureter having a casing formed with an air passage through the same and an air valve slideable transversely of said air passage and having two portions which intercept the air passage at a distance from each other, the said air passage being triangular in cross section between the said two portions of the valve and having its apex away 120 from the valve and a fuel metering pin connected to and movable by said air valve and having formed therein a groove of increasing cross section forming a fuel orifice, 125 located adjacent the apex of the air passage, and a tube within which a portion of the 130

metering pin is received, said tube being movable to vary the relative position of the fuel orifice.

13. A casing having an air passage there-
5 through which is of increasing cross section
from one side thereof to the other, a cylinder
subjected to changes in pressure in the
intake manifold, a piston in the cylinder, a
valve forming part of said piston and inter-
10 cepting said air passage, and a fuel valve
having a fuel opening of increasing cross
section, said fuel valve being rigidly secured
to the air valve.

14. A carbureter having a casing formed
15 with an air passage through the same, an air
valve slideable transversely of said air pas-
sage and having two portions which inter-
cept the air passage at a distance from each
20 other, the said air passage being triangular
in cross section between the said two por-
tions of the valve and a fuel metering rod
secured to said air valve and passing trans-
versely through the said air passage at the
25 apex and the middle of the base thereof, said
rod being formed with a longitudinal groove
of increasing cross section therein, the
smaller cross section of the groove being
toward the base side of the air passage.

15. A carbureter having a casing formed
30 with an air passage therethrough which is
of increasing cross section from one side
thereof to the other, a cylinder subjected to
changes in pressure in the intake manifold,
a piston in the cylinder and provided with
35 flanges which intercept the said air passage

and a fuel metering pin secured to the cen-
ter of said piston and passing through the
said air passage transversely thereof and
provided with a groove of increasing cross
section, the base of the triangle formed by 40
cross section of the air passage and the point
of least cross section of the groove in the
metering pin being toward the piston.

16. A carbureter having a casing formed
of a combined hollow cylinder and a plug 45
having an air passage transversely through
the same of increasing area from the bottom
to the top, the cylinder portion of the cas-
ing being formed with inlet and outlet open-
ings to and from said passage in the plug, 50
the casing being formed with a cylindrical
slot between the cylinder and plug portion
of the casing, and a piston air valve movable
in said slot and having portions which move
transversely of said air passage to open and 55
close the same.

17. In a carbureter, a casing having an air
passage therethrough which is of increasing
cross-section from the bottom thereof to the
top, a cylinder subjected to changes in pres- 60
sure in the intake manifold, a piston in the
cylinder actuated in one direction by gravity
and in the other direction by changes in
pressure in the cylinder, a valve forming
part of said piston and intercepting said air 65
passage, and a fuel valve having a fuel open-
ing of increasing cross-section, said fuel
valve being moved by said piston.

In testimony whereof I affix my signature.
EMIL HUBER.

Corrections in Letters Patent No. 1,344,696.

It is hereby certified that in Letters Patent No. 1,344,696, granted June 29, 1920, upon the application of Emil Huber, of Detroit, Michigan, for an improvement in "Carburetors," errors appear in the printed specification requiring correction as follows: Page 1, line 34, for patent number "708,949" read 780,949; page 2, line 119 for the word "port" read part; and that the said Letters Patent should be read with these corrections therein that the same may conform to the record of the case in the Patent Office.

Signed and sealed this 3d day of August, A. D., 1920.

[SEAL.]

R. F. WHITEHEAD,

Acting Commissioner of Patents.

CL 261—49.
